UNITED STATES PATENT OFFICE.

ISIDOR ROSEN, OF BROOKLYN, NEW YORK.

DESIGN FOR A GAME BOARD.

Application filed April 7, 1926. Serial No. 17,204. Term of patent 7 years.

To all whom it may concern:

Be it known that I, ISIDOR ROSEN, a citizen of the United States of America, residing at Brooklyn, Kings County, State of New York, have invented a new, original, and ornamental Design for a Game Board, of which the following is a specification, drawing, forming part hereof, in which—

Fig. 1 illustrates a face view of a game board showing my new design, and Fig. 2 is an end view thereof.

I claim—

The ornamental design for a game board as shown.

Signed at New York city, New York, this 3rd day of April, 1926.

ISIDOR ROSEN.
